UNITED STATES PATENT OFFICE.

GEORGE MAURICE WRIGHT, OF LONDON, ENGLAND, ASSIGNOR TO MARCONI WIRELESS TELEGRAPH COMPANY OF AMERICA, OF NEW YORK, N. Y., A CORPORATION OF NEW JERSEY.

VALVE-RECEIVER FOR WIRELESS SIGNALS.

1,238,869.

Specification of Letters Patent.

Patented Sept. 4, 1917.

Application filed March 13, 1917. Serial No. 154,579.

To all whom it may concern:

Be it known that I, GEORGE MAURICE WRIGHT, a subject of the King of Great Britain, and resident of Marconi House, Strand, 5 London, England, have invented a new and useful Improvement in Valve-receivers for Wireless Signals, of which the following is a specification.

This invention relates to receivers of wireless signals which comprise a vacuous vessel containing a heated filament, a grid and an anode.

According to this invention I employ two grids between the filament and the anode. 15 By this means I am enabled to limit the strength of the current in the anode circuit.

One important result of this will be that the sounds caused by atmospherics in a telephone will be reduced and will thus be prevented from overpowering the sounds caused 20 by the signals which it is desired to detect.

My invention is illustrated by the accompanying drawings, Figure 1 of which is a diagram of the circuits of a receiver for 25 wireless signals. Fig. 2 shows the construction of the vacuum tube with the fine and coarse mesh screens located between the filament and anode.

In Figs. 1 and 2 *a* is a vacuous tube in- 30 closing a filament *b* heated by a battery *c*, a grid *d*, a second grid *D* and an anode *e*. In Fig. 2 an inductance *f* shunted by a condenser *g* is connected to the outer grid *D* and to the inner grid *d* through a resistance *h* 35 across a battery *C* and is coupled to an aerial *i*. A second inductance *k* shunted by a condenser *l* is connected to the anode *e* and through a high tension battery *m* to the inner grid *d* and is coupled to a receiver *n*. 40 A coil *o* in the system *f g* is so positioned as to enable the coupling to be varied between the oscillatory circuit *f g* and the oscillatory circuit *k l*. The coil *o* in the position shown in Fig. 1 does not permit signals, no matter how strong, to get through unless the filament is incandescent. Without 45 this arrangement, signals would manage to get through the vacuous tube, owing to the natural capacity of the tube, the leads, etc. 50 A fixed potential is maintained between the grid *d* and the filament by means of a potentiometer *p*.

The grid *d* should be of fine mesh and

should form a complete screen across the path between the filament and the anode. 55 The function of the screens, located between the filament and anode, is to reduce the direct flow of electrons from the incandescent filament to the anode. The outer grid may be constructed as required, the properties of 60 fine and coarse mesh for magnifying purposes being well known.

What I claim is:

1. A vacuous tube containing a heated filament, a grid of coarse mesh, a second grid 65 of fine mesh disposed between the first mentioned grid and the filament, an anode, an oscillatory circuit connected to the filament and the coarse mesh grid, and a second oscillatory circuit connected to the fine mesh grid 70 and to the anode.

2. A vacuous tube containing a heated filament, a grid of coarse mesh, a second grid of fine mesh disposed between the first mentioned grid and the filament, an anode, an 75 oscillatory circuit connected to the filament and the coarse mesh grid, and a second oscillatory circuit containing a high potential battery, connected to the fine mesh grid and to the anode.

3. A vacuous tube containing a heated filament, a grid of coarse mesh, a second grid of fine mesh disposed between the first mentioned grid and the filament, an anode, an oscillatory circuit connected to the filament 85 and the coarse mesh grid, and a second oscillatory circuit containing a high potential battery, connected to the fine mesh grid and to the anode, the two circuits being inductively coupled exterior of said tube. 90

4. A vacuous tube containing a heated filament, a grid of coarse mesh, a second grid of fine mesh disposed between the first mentioned grid and the filament, an anode, an oscillatory circuit connected to the filament 95 and the coarse mesh grid, and a second oscillatory circuit containing a high potential battery, connected to the fine mesh grid and to the anode, the two circuits being inductively coupled exterior of said tube, and electrically connected to each other through a battery shunted by a resistance. 100

In testimony that I claim the foregoing as my invention, I have signed my name this 16th day of February, 1917.

GEORGE MAURICE WRIGHT.
